(57) **CLAIM**

The ornamental design for a wireless headset communications device, as shown and described.

DESCRIPTION

1. Wireless headset communications device

1.1 : Perspective

1.2 : Front

1.3 : Back

1.4 : Left

1.5 : Right

1.6 : Top

1.7 : Bottom

The gist of the present ornamental design is a combination of shape and pattern of a wireless headset communications device, as shown and described.
